FIG.3.

FIG. 4.

FIG. 5.

FIG. 6.

FIG. 1 is a perspective view of a combined lamp bulb display and container unit embodying my new design;

FIG. 2 is a perspective view thereof, showing the lamp-and-tray portion partly withdrawn from the container;

FIGS. 3 and 4 are views corresponding to FIGS. 1 and 2, respectively, but showing another embodiment of my new design; and

FIGS. 5 and 6 are views corresponding to FIGS. 1 and 2, respectively, of still another embodiment of my new design.

This application is a continuation of my earlier applications, Serial Nos. D. 55,840, D. 55,841 and D. 55,842, filed May 8, 1959, now abandoned.

The sides and ends of the containers hidden from view in the drawings are identical to those which are shown.

The dominant features of my new design reside in the portions shown in full lines.

The characteristic feature of my new design resides in the particular tray element of the combination, said tray having compartments and stops shaped as shown.

I claim:

The ornamental design for a combined lamp bulb display and container unit, substantially as shown and described.
